C. W. BARNES

IGNITION DEVICE

Filed March 2, 1925

UNITED STATES PATENT OFFICE.

CLARENCE W. BARNES, OF SIOUX CITY, IOWA.

IGNITION DEVICE.

Application filed March 2, 1925. Serial No. 12,559.

My invention relates to an ignition device combining the functions of the ordinary spark plug and timing and distributing mechanism commonly used in the internal 5 combustion engine.

My invention embodies, generally, a firing pin extended through the engine housing of an internal combustion engine mounted for longitudinal sliding movement in suitably 10 insulated bearings, adapted to move to proximity with a stationary electrode at one extremity of its sliding path so as to produce a spark at that point, actuated by a revolving cam carried by the ordinary valve actuating cam shaft, or by an auxiliary cam shaft driven in a similar manner to the ordinary cam shaft.

A further object is to so arrange the parts that the firing pin will not produce a spark 20 until after it has moved to a point within a certain radius from the stationary electrode, thereby insuring accuracy of timing.

More specifically, referring to the preceding object, it is my purpose to provide a firing pin actuated by a cam which has a bearing face insulated during a portion of its periphery from the cam shaft, and having a portion of its face in electrical connection with the cam shaft, the latter portion being 30 designed to establish a circuit through the firing pin after the firing pin has reached a certain predetermined proximity to the stationary electrode.

Another object is to provide means with 35 such a firing pin for advancing or retarding the timing of the spark from the dash of an automobile embodying my invention.

A further object is to provide suitable 40 means for mounting the firing pin in an engine housing so as to allow removal thereof, to provide for spring pressure to maintain constant contact of the firing pin with the cam, to allow adjustment of such spring pressure and to provide a semi-permanent 45 shell extending through the water jacket to protect the firing pin from the water, and to prevent leakage of the water when the firing pin is removed.

With these and other objects in view, my 50 invention consists in the construction, arrangement and combination of the various parts of my device, whereby the objects con-

templated are attained, as hereinafter more fully set forth, pointed out in my claims and and illustrated in the accompanying drawings, in which:

Fig. 1 is a transverse sectional view through a portion of the engine with my invention embodied therein, the figure being partly diagrammatic to illustrate the electrical circuit employed in my invention.

Fig. 2 is an elevation of a portion of the engine head, illustrating the spark advancing and retarding mechanism.

Fig. 3 is an elevation of the lower portion 65 of the engine housing, a portion thereof being broken away to illustrate the cam shaft.

Fig. 4 is a partly sectional, partly diagrammatical view, illustrating a somewhat modified form of my invention.

I have used the reference character 10 to indicate the water jacket of an engine housing. The wall of the cylinder is indicated at 11 and the cam shaft housing at 12. The cylinder head, 13, is provided with the combustion chamber space, 14, into which is ordinarily extended a spark plug.

It will be understood that the type of motor illustrated is the ordinary T-type, but that my invention could be adapted to 80 other types of engine.

A cam shaft, 18, is journaled in the housing, 12. The cam shaft, 18, may be driven similarly to the ordinary cam shaft, or may be embodied in the ordinary cam shaft, and 85 the details of the driving mechanism are therefore not illustrated.

For each cylinder, 11, I provide one of the firing devices, which is preferably situated between the exhaust and intake valves of the 90 respective cylinders so as to be centered laterally relative to the respective cylinders. The position of the cam relative to the valve-operating cams, 15, is shown in Fig. 3. The ordinary valve tappets are shown at 16, extending through posts, 17, on the housing, 12.

Each ignition device includes an upper semi-permanent casing, A, extending through the water jacket, 10, a lower removable casing, B, traversing the space between the water jacket, 10, and the crank case, 12, and a sliding firing pin, C. The upper casing, A, comprises a cylindrical shell, 19,

threaded at 20, through the upper wall of the water jacket, 10, and extending into the explosion chamber, 14, and an inner bushing, 20^a, insulated from the shell, 19, by means 5 of the porcelain or other suitable insulating material, 21.

The lower end of the shell, 19, is provided with a squared collar, 22, to which a wrench may be fitted in inserting the shell, 19, and 10 which also serves to engage a gasket, 23, against the under face of the lower wall of the water jacket, 10, in order to provide a fluid-tight joint. The shell, 19, extends somewhat below the collar, 22, and is received in the upper end of the casing, B.

The firing pin unit is assembled within a tabular metallic jacket, 24, which is slidably mounted in the casing, B. The casing, B, at its lower end is enlarged, as at 20 25, to receive a spring, 26, compressed between the shoulder formed by the enlargement, 25, and a nut, 27, threaded onto the end of the jacket, 24.

It may be mentioned at this point that the 25 casing, 24, together with the firing pin, C, are inserted in place from within the crank case, 12, by being extended upwardly through the opening, 28, provided in the crank case to receive the enlargement, 25.

30 Fixed within the jacket, 24, by means of the porcelain filling, 21, is the bearing sleeve, 20^a.

A tappet, 34, is secured by the insulating material, 29, and together with the jacket, 35, forms a rigid unitary structure in the 35 lower portion of the firing pin.

Secured on the cam shaft, 18, is a cam, D, comprising a metallic cam sleeve, 35, and the cam proper, 36. The sleeve, 35, is secured to an enlarged portion, 37, of the cam shaft, 18, by means of a set screw, 38. Thus the sleeve, 35, may be slipped over the cam, 15, in removing for repair purposes or in adjusting for timing. The cam ordinarily turns in the direction indicated by the arrow 40 in Fig. 1, and in the lifting face of the cam is inserted a collar of insulating material, 39, extending to a point just short of the peak of the cam.

50 The firing pin, C, is held in engagement with the cam, D, by means of a spring, 26, only the tappet, 34, being in contact with the face of the cam.

The firing pin electrode, 40, is provided 55 at its lower end with a binding post, 41, and a nut, 42, to receive an electrical connection, 43. The lower end of the electrode, 40, is secured in the insulating material, 29, and the upper end slidably mounted in the sleeve, 20^a.

The tappet, 34, is likewise provided with a binding post, 44, and a nut, 45, securing a conductor, 46. Current may be supplied 60 from any source of high tension current, such as the induction coil, 47, actuated from

a source of low tension current, 48, and having its secondary connected to the tappet, 34, and electrode, 40, through the medium of the conductors, 43 and 46, respectively. 70

It will be understood that the coil, 47, supplies current to each of the several ignition devices which are connected in parallel, all of the electrodes, 40, being connected to the conductor, 43, and all of the tappets, 34, 75 being connected to the conductor, 46.

I provide an upper electrode, 49, which is mounted for sliding movement against spring pressure as follows. A hollow plug, 50, is threaded at 51 into the upper wall of 80 the chamber, 14, and has a polygonal head, 52, to which a wrench may be fitted, and which engages the upper surface of the engine head through the medium of a gasket, 53, serving to secure the plug in engagement 85 with the cylinder head.

A headed bushing, 54, is threaded into the upper open end of the plug, 50, and is provided with an opening through which the electrode, 40, is slidably received. Between 90 the lower face of the bushing, 54, and a shoulder, 55, formed on the electrode, 49, is a spring, 56, tending to urge the electrode, 49, downwardly. The upper end of the electrode, 49, is threaded to receive an adjustable head, 57, adapted to engage the prongs, 58, of a pivoted timing fork, 59, and thus to limit the down movement of the electrode, 49.

The fork, 59, is mounted on a shaft, 60, 100 extending longitudinally of the engine through brackets, 61, and oscillating movement is transmitted through the shaft, 60, to the fork, 59, by means of an arm, 62, fixed to the shaft, 60, and a link, 63, extending from the arm, 62, to the ordinary spark control shaft of the vehicle. 105

It will now be seen that as the cam, 36, is rotated, as indicated by the arrow, the insulating face, 39, will first engage the tappet, 34, and break the connection therewith to the engine housing. The firing pin will then be raised through the medium of the tappet until the lower electrode, 40, has either approached within firing distance of the upper electrode, 49, or has engaged it as shown in Fig. 1, at which time contact will be established through the two electrodes between the induction coil and the engine housing. 110 When the peak of the cam reaches the tappet, 34, the circuit will be completed through the tappet, 34, and the cam shaft, 18, to the engine housing, and after the electrodes are then spaced apart a spark will occur at 115 that point. After the electrodes are in contact the spark will occur when the cam has rotated sufficiently to allow the electrodes to separate. 120

The parts are preferably arranged so that 125 when the spark lever is in extreme advanced 130

position the fork, 58, will lift the upper electrode, 49, to such a point that the lower electrode, 40, will merely contact with the upper electrode, 49, without lifting it any appreciable distance. Thus when the engine is running at high speed the action of the ignition device will be smoother than if the upper electrodes were being lifted appreciably.

10 When the spark lever is retarded the fork, 58, will be lowered to such a position that the electrode, 49, will be raised a considerable distance by the firing pin has receded substantially. Thus the points will not separate until the cam, 36, has traveled a distance considerably beyond the point shown in Fig. 1, so as to lower the firing pin, and the spark will thus occur at a later time.

The parts may be so arranged that the electrodes will merely approach within firing distance and then recede when the spark is advanced position, although one disadvantage in such an arrangement lies in the fact that the spark would also tend to occur between the cam and the tappet, 34, and to burn out the insulation, 39.

I have found from experiment that where the firing pin is constantly grounded to the engine such premature firing will occur and that good results are not obtained thereby. I attribute this to the fact that the resistance of the circuit will vary under varying conditions of lubrication, of the strength of current applied to the induction coil, and of possible clogging to a certain extent of the electrodes by carbon or other foreign material. Under these varying conditions of resistance the arc will not be established at accurately regular intervals. That is, at some times it will occur too soon, and at other times too late.

By bringing the electrode, 40, within a certain predetermined distance, much less than that at which an arc would ordinarily commence, and then grounding the firing pin to the frame of the engine, it will be seen that the time of the spark can be much more accurately controlled. This is attained by insulating the cam, 36, during that portion of the rise in which the electrode, 42, is brought to the proper position relative to the stationary electrode, 16. Upon contact of the tappet, 34, with the portion, 36, a circuit will be completed through the firing pin, C, the body of the engine, and the induction coil, 47.

In the form here shown the actual spark will not occur until the tappet has passed the hump of the cam. The spark will then occur upon separation of the points.

I find that there are some advantages in allowing the electrodes to actually contact at all times. For instance, the contact of the electrodes helps to keep the faces thereof clean, and in some cases a direct low ten-

sion current may be used, and the spark produced by the interrupting of the flow of the electricity.

Another advantage of bringing the points always together lies in the fact that during the period of separation the points will very rapidly traverse all of the possible relative positions of spacing between the two electrodes, and the trouble sometimes experienced in the ordinary spark plug of incorrect spacing of electrodes will not be manifest.

The tension upon the spring, 26, may be varied by rotating the retaining nut, 27, and may further be adjusted from the exterior of the engine by rotating the threaded nut received on the upper end of the casing, B, and engaging the lower wall of the water jacket, 10.

In order to allow access to the ends of the electrode and tappet, the casing, B, and the jacket, 24, are apertured, as shown in Fig. 1.

In order to adjust the timing the cam, D, may be rotated on the shaft, 18, and secured in the proper position by means of the set screw, 38. Where the ordinary cam shaft is used the cam, D, may be formed in two sections, or made large enough in diameter to slip over the valve raising means as shown.

In Fig. 4, I have shown a slightly different arrangement of the parts of the electrical circuit and upper contact member, in which the contact, 49^a, is insulated by means of an insulating sleeve, 49^b, slidably mounted in the fork, 50^a, in the same manner that the electrode, 49, is mounted in the plug, 50. The head, 57^a, is threaded to the upper end of the insulating sleeve, 49^b. The upper end of the electrode, 49^a, is threaded and provided with nuts, 49^c, and 49^d, to receive a connector, 49^e. A portion of the upper end of the lower electrode, 40, is illustrated in the diagram, and a portion of the lower end of the tappet, 34. The two are connected as indicated at 49^f, by some form of connector, replacing the wires, 43 and 46. One side of the induction coil secondary is grounded, as at 49^g, and the circuit is thus completed through the engine housing, induction coil, the connector, 49^e, the electrodes, 49^a, and 40, the tappet, 34, and the cam, 36, when the hump of the cam is reached.

In order to prevent rotation of the firing pin relative to the casing, B, a small screw, 64, is secured in the jacket, 24, and slidably extended through the slot, 65, in the casing, B.

Some changes may be made in the construction and arrangement of the parts of my invention without departing from the real spirit and purpose of my invention, and it is my intention to cover by my claims any

modified forms of structure or use of mechanical equivalents which may reasonably be included within their scope.

I claim as my invention:

- 5 1. In combination with an engine housing having an explosion chamber, a cam shaft journalled in said housing, a cam on the shaft having a bearing face insulated during a portion of its periphery from the cam shaft and electrically connected thereto during the remainder of its periphery, a firing pin slidably mounted relative to the housing and insulated therefrom, said firing pin having an end extending into the explosion chamber and its other end engaged against the cam, an electrode supported in the engine housing above the firing pin, and a circuit including a source of high tension current, said electrode, and the engine housing, the cam in rotating serving first to establish electrical communication between the firing pin and electrode, then to complete the circuit by grounding the firing pin to the engine housing, and then to break the circuit between the firing pin and electrode while maintaining the firing pin in grounded relation to the engine housing.
- 20 2. In combination with an engine housing having an explosion chamber, a cam shaft journalled in said housing, a cam on the shaft having a bearing face insulated during a portion of its periphery from the cam shaft and electrically connected thereto during the remainder of its periphery, a firing pin slidably mounted relative to the housing and insulated therefrom, said firing pin having an end extending into the explosion chamber and its other end engaged against the cam, an electrode supported in the engine housing above the firing pin, and a circuit including a source of high tension current, said electrode, and the engine housing, the cam in rotating serving first to establish electrical communication between the firing pin and electrode, and then to complete the circuit by grounding the firing pin to the engine housing.
- 25 3. In combination with an engine housing having an explosion chamber, a cam shaft journalled in said housing, a cam on the shaft having a bearing face insulated during a portion of its periphery from the cam shaft and electrically connected thereto during the remainder of its periphery, a firing pin slidably mounted relative to the housing and insulated therefrom, said firing pin having an end extending into the explosion chamber and its other end engaged against the cam, an electrode supported in the engine housing above the firing pin, and a circuit including a source of high tension current, said electrode, and the engine housing, the cam in rotating serving first to establish electrical communication between the firing pin and electrode, and then to complete the circuit by grounding the firing pin to the engine housing.
- 40 4. In combination with an engine housing having an explosion chamber, a firing pin mounted relative to the housing for sliding movement, and having an end extending into the explosion chamber, an electrode supported in the engine housing above the firing pin, a circuit including a source of high tension current, the electrode, the firing pin and the engine housing, and means serving first to establish electrical communication between the firing pin and electrode, and then to complete the circuit by grounding the firing pin to the engine housing.
- 45 5. In combination with an engine housing having an explosion chamber, a firing pin mounted relative to the housing for sliding movement, and having an end extending into the explosion chamber, an electrode supported in the engine housing above the firing pin, means for adjusting said electrode toward or from said firing pin so as to retard or advance the moment of firing between said electrodes, a circuit including a source of high tension current, the electrode, the firing pin and the engine housing, and means serving first to establish electrical communication between the firing pin and electrode, and then to complete the circuit by grounding the firing pin to the engine housing.

having an explosion chamber, a firing pin mounted relative to the housing for sliding movement, and having an end extending into the explosion chamber, an electrode supported in the engine housing above the firing pin, a circuit including a source of high tension current, the electrode, the firing pin and the engine housing, and means serving first to establish electrical communication between the firing pin and electrode, then to complete the circuit by grounding the firing pin to the engine housing, and then to break the circuit between the firing pin and electrode while maintaining the firing pin in grounded relation to the engine housing.

4. In combination with an engine housing having an explosion chamber, a firing pin mounted relative to the housing for sliding movement, and having an end extending into the explosion chamber, an electrode supported in the engine housing above the firing pin, a circuit including a source of high tension current, the electrode, the firing pin and the engine housing, and means serving first to establish electrical communication between the firing pin and electrode, and then to complete the circuit by grounding the firing pin to the engine housing.

5. In combination with an engine housing having an explosion chamber, a firing pin mounted relative to the housing for sliding movement, and having an end extending into the explosion chamber, an electrode supported in the engine housing above the firing pin, means for adjusting said electrode toward or from said firing pin so as to retard or advance the moment of firing between said electrodes, a circuit including a source of high tension current, the electrode, the firing pin and the engine housing, and means serving first to establish electrical communication between the firing pin and electrode, and then to complete the circuit by grounding the firing pin to the engine housing.

Signed at Sioux City, in the county of Woodbury and State of Iowa, this 26th day of February, 1925.

CLARENCE W. BARNES.
